CLAIM

The ornamental design for a food tray, as shown and described.

DESCRIPTION

FIG. 1 is a top front perspective view of a food tray, showing my new design;

FIG. 2 is a bottom front perspective view thereof;

FIG. 3 is a top plan view thereof;

FIG. 4 is a front elevation view thereof, with the rear elevation view being a mirror image thereof;

FIG. 5 is a bottom plan view thereof;

FIG. 6 is a right side elevation view thereof, with the left side elevation view being a mirror image thereof; and,

FIG. 7 is a sectional view thereof, taken along line 7-7 of FIG. 3.

1 Claim, 4 Drawing Sheets
